ABSTRACT OF THE DISCLOSURE

This invention relates to a process whereby saturated aliphatic carboxylic acids or their preformed metal salts are converted to their corresponding N-methylaldimine or N-ethylaldimine analogs. More specifically, this process involves treating the carboxylic acid or its preformed metal salt in methylamine or ethylamine with lithium metal to form its analogous N-methylaldimine or N-ethylaldimine.

The existing methods for the preparation of N-alkylated aldimines from carboxylic acids involves the initial conversion of the carboxylic acid to its aldehyde analog (which usually involves several discrete steps) followed by reaction of the aldehyde with a primary amine to produce the N-alkylated aldimine. It is the object of the present invention to provide a process whereby this conversion of a carboxylic acid to the N-methylaldimine or N-ethylaldimine may be effected in a single direct step.

It has been found that the object of the invention may be accomplished by reaction of a solution of the acid or its metal salt in methylamine or ethylamine with lithium metal and maintaining non-acidic conditions during the product isolation procedure.

DISCLOSURE

This invention relates to a process for converting certain saturated aliphatic carboxylic acids into their corresponding N-methylaldimine or N-ethylaldimine analogs.

The prior state of the art is defined by the patent, U.S. 1,834,850, patented Dec. 1, 1931 and granted to Walter Kropp. This patent discloses a process for the preparation of unsaturated aldimines by condensing alpha-beta-substituted acroleins with primary aromatic amines.

This invention is totally unlike the process described in the cited patent in that a saturated carboxylic acid, rather than an unsaturated aldehyde, is a reactant. Moreover a primary aliphatic amine, rather than a primary aromatic amine, is employed in this invention. Finally a totally different type of chemical reaction is involved in this invention, namely reduction of a carboxylic acid rather than condensation of an aldehyde with an amine.

The acids suitably employed in the process of this invention are straight chain or branched chain saturated aliphatic carboxylic acids containing three or more carbon atoms. Best results are obtained with acids containing more than five carbon atoms. The acids may be used either in the form of the pure acid or in the form of its metal salt. If the free acid or the salt of a metal other than lithium is used, its lithium salt is formed *in situ*.

In the process lithium is preferably employed in a slightly greater than 3:1 molar ratio of lithium to carboxyl group. Thus 3 gram-atoms of lithium are necessary to convert 1 mole of a saturated monocarboxylic acid to its aldimine analog or 6 gram-atoms are required to convert 1 mole of a saturated dicarboxylic acid to the dialdimine. If the lithium salt of the acid is used, 2 gram-atoms of lithium are required for the conversion of monacid to aldimine; however, if other metal salts are used, 3 gram-

2

atoms of lithium are required because the other metal precipitates as the first gram-atom of lithium is added.

The process of the invention is conducted by the addition of the proper amount of lithium metal to a solution of the carboxylic acid or its salt in methylamine or ethylamine. Alternatively the carboxylic acid or its salt may be added to a solution of lithium in methylamine or ethylamine. The usual temperature of the process is that of refluxing amine, about -6° C. for methylamine and approximately 17° C. for ethylamine. The process is typically conducted at atmospheric pressure, but greater pressures are not prohibited. After eight hours or loss of blue coloration, the reaction is quenched by addition of water, ammonium chloride, alcohol or a mixture of these compounds, the solutions remaining basic under these conditions. (When non-lithium salts are used, the precipitated metals are recovered best by mechanical methods prior to quenching.) From the resulting solution the amine solvent may then be recovered by distillation. The N-alkylated aldimine product of the process may be obtained by distillation or extraction with suitable solvents such as pentane or diethyl ether. Any unreacted acid remaining in the reaction vessel after removal of the aldimine product may be recovered from its metal salt by acidification of the solution and extraction. The lithium used in the reaction can be recovered in the form of a salt.

The product of the process is an N-methyl- or an N-ethylaldimine. For example, from the reaction of lithium with pentanoic acid in methylamine is obtained N-pentylidenemethylamine; from lithium with decanoic acid in ethylamine is obtained N-decylidenethylamine, etc.

A series of reductions of saturated carboxylic acids was conducted employing methylamine and lithium metal. Typically the acid was dissolved in the methylamine solvent and the lithium metal added to the solution. The mixture was stirred until the blue color disappeared or for 8 hours for monoacids and up to 15 hours for diacids. The reaction was then quenched with water, extracted with pentane or diethyl ether and the product isolated by distillation and analyzed by gas-liquid chromatography. The results of this series are shown in Table I.

TABLE I

Acid	Amount (moles)	Lithium (g.-atoms)	Methylamine (ml.)	Reaction time (hrs.)	Percent conversion
Propionic-----	0.250	0.750	500	3.5	15
Butyric-----	0.250	0.750	500	5	21
Pentanoic-----	0.250	0.750	500	4.5	68
Neopentanoic-----	0.250	0.750	500	3	15
Neoheptanoic-----	0.250	0.750	500	3	62
Octanoic-----	0.250	0.750	500	2	59
Decanoic-----	0.250	0.750	1000	7.5	69
Dodecanoic-----	0.10	0.30	600	8	61
Tetradecanoic-----	0.062	0.186	600	8	84
Hexadecanoic-----	0.062	0.25	600	6.5	33
Octadecanoic-----	0.062	0.25	1000	8	Trace
Cyclohexanoic-----	0.250	0.810	500	5	65
Isopentanoic-----	0.250	0.810	500	8	43
Butandioic-----	0.250	1.50	1000	8	15
Hexandioic-----	0.250	1.50	1000	8	25
Nonandioic-----	0.250	1.50	1000	12	58

EXAMPLE II

A series of reactions was conducted by the procedure of Example I with ethylamine as the solvent.

Acid	Amount (moles)	Lithium (g.-atoms)	Ethyl amine (ml.)	Reaction time (hrs.)	Percent conversion
Butyric-----	0.250	0.810	500	5	36
Decanoic-----	0.125	0.375	500	8	88
Octadecanoic-----	0.100	0.300	500	6	61
Cyclohexanoic-----	0.250	0.810	500	8	70

3
EXAMPLE III

A series of reactions was conducted by the procedure of Example I but using the lithium, sodium, iron, and potassium salts.

Acid salt	Amount (moles)	Lithium (g.-atoms)	Methyl amine (ml.)	Reaction time (hrs.)	Percent conversion	
Lithium decanoate-----	0.062	0.20	400	5	95	10
Potassium pentanoate-----	0.250	0.810	500	8	61	
Sodium pentanoate-----	0.250	0.810	500	6	60	
Lithium pentanoate-----	0.250	0.560	500	5	65	
Iron (III) pentanoate-----	0.10	1.0	500	6	57	15

We claim:

1. A process for converting the lithium salt of a saturated unsubstituted aliphatic mono or di carboxylic acid containing 3 or more carbon atoms to the corresponding N-methylaldimine or N-ethylaldimine analog which comprises reacting at reflux temperature a methylamine or ethylamine solution of said carboxylic acid lithium salt with lithium metal in at least 2:1 mole ratio amounts relative to the carboxylic acid salt groupings of the carboxylic acid salt and recovering the N-methylaldimine or the N-ethylaldimine from the reaction mixture.

2. A process according to claim 1 wherein the lithium salt is formed *in situ* by reacting said carboxylic acid with lithium metal in at least 3:1 mole ratio amounts relative to the free carboxyl groups of the acid.

4

3. A process according to claim 1 wherein the lithium salt is formed *in situ* by reacting a metal salt, other than the lithium salt, of said carboxylic acid with lithium metal in at least 3:1 mole ratio amounts relative to the free carboxyl groups of the acid.
